UNITED STATES PATENT OFFICE.

FRITZ ALBERT PETTERSSON, OF HALMSTAD, SWEDEN, ASSIGNOR TO AKTIEBOLAGET
GJUTERIMASKINER, A COMPANY LTD., OF HALMSTAD, SWEDEN.

COOKING STOVE.

Application filed November 21, 1922. Serial No. 602,444.

To all whom it may concern:

Be it known that I, FRITZ ALBERT PETTERSSON, subject of the King of Sweden, residing at Halmstad, Sweden, have invented certain new and useful Improvements in Cooking Stoves, of which the following is a specification.

The present invention relates to a cooking stove containing a baking oven and a hot water container, in which the latter is composed of several elements, situated at the back of the stove. According to this invention two dampers are arranged in the smoke flue of the stove, the one at the entrance to the flue around the said elements and the other in the flue around the baking oven. The said dampers are arranged in such a manner that when the damper in the element flue is open and the other damper shut the gases from the fire flow directly between the two elements of the hot water container, which are situated nearest to the fire place and from thence between the other elements, whilst in the reverse position of the dampers the gases from the fire place are caused to flow through the flue around the baking oven and from thence to the flue of the hot water containing elements, without, however, passing through that part of the said flue which is situated between the two elements nearest the fire place.

A constructional form of the invention is illustrated in the accompanying drawing, on which Fig. 1 is a vertical longitudinal section of the stove and Fig. 2 is a vertical cross section on the line II-II (Fig. 1).

1 is the fireplace, between which and the smoke outlet 2 the hot water container, heated by the gases from the fire place, is situated. This container in the form, illustrated as an example, consists of three elements 3, 4 and 5, communicating with and secured behind one another in such a manner that vertical channels or passages 6, 7 are formed between them. The front element 3 forms the back wall of the fireplace 1, and has an upper central opening 8 through which the gases from the fire may pass to the vertical passage 6 between that element 3 and the intermediate

element 4, as illustrated by the arrows, Fig. 2. The intermediate element 4 is made with a central opening 9 in its lower part and the rear element 5 is made with a central opening near its upper end so that the gases 55 may flow from the said passage 6 to a vertical passage 7 between the intermediate and rear elements 4, 5 and after passing upwards through said passage 7 may flow directly to the smoke outlet 2. A damper 11 60 is arranged at the said opening 8 and by means of this damper 11 the fire gases—if desired—may be prevented from entering the said passage 6. When the damper 11 is open (the position illustrated in full lines 65 in Fig. 2), the fire gases thus flow down through the passage 6, through the opening 9 and upwardly through the passage 7 between the two elements 4 and 5, and from thence through the opening in the element 5 70 to the smoke outlet 2. The passages 6, 9 and 7 thus constitute flues which may convey the fire gases between the said elements to heat the water therein.

The baking oven 10 is located at one side 75 of the fire-space and of the water heater, and extending across the top of the oven 10 is a passage 16 which communicates with a passage 17 at the side of the oven, which passage 17 communicates in turn with a bottom passage 18 from whence the gases may pass downwards (as indicated by the arrows in Fig. 1) to the aforesaid passage 9 and from thence by the passage 7 to the outlet 2. At the junction of the passage 17 with the 80 passage 18 is provided a damper 12 which in its closed position prevents the fire gases from passing from the fire place 1 through the passages 16, 17, 18 around the baking oven to the passage 9. Whilst the damper 12 is preferably situated between the passages 17, 18 as shown, it may obviously be situated at any position in the said passages.

This cooking stove and water heater operates in the following manner:—When the 85 damper 11 is open and the damper 12 shut (thus closing the passage through the passages 16, 17 and 18 around the baking oven) the hot gases from the fire place 1 flow through the opening 8 in the upper part of 100

the element 3 and pass downwards through the passage 6, through the passage 9 and upwardly through the passage 7 to the smoke outlet 2, whereby the water in the elements 3, 4, 5 becomes heated to a high temperature. If it be desired to heat the baking oven 10, the damper 11 must be closed and the damper 12 opened, so that the hot gases are caused to pass through the passages 16, 17, 18 around the baking oven 10 and from the passage 18 to the passage 9 and from thence to the passage 7, without flowing through the passage 6 between the front and the intermediate elements of the water heater.

15 The damper 11 is loosely fitted in a recess in the upper part of the intermediate element 4, the damper door itself being pivoted in a frame 19, provided with grooves 20 or flanges at the sides and the lower edge, 20 which grooves or flanges cooperate with corresponding flanges 21 or grooves in the said element 4. By means of this arrangement a very simple construction of damper is provided, and moreover, a third passage for the 25 fire gases may be provided by moving the damper 11 so that the gases from the fire place may flow freely through the opening in the upper part of the element 4 (otherwise occupied by the damper) directly to 30 the smoke outlet 2, and without flowing through the passages 6, 9, 7 or through the passages 16, 17, 18.

Having now particularly described the nature of my invention and the manner of 35 its operation, what I claim is:

1. A cooking stove and water heater comprising,—a fireplace, a water heater located behind the fireplace and comprising front, intermediate and rear water containing elements spaced from each other to form vertical front and rear passages for the fire 40 gases, a baking oven located at one side of the fireplace, means around the oven forming passages for directing the fire gases over the top of the oven, thence down one 45 side, and thence beneath the bottom thereof, means forming a passage for directing the said gases from beneath the oven to the said vertical rear passage between the intermediate and rear water containing elements, and control means for the fire gases comprising a damper for shutting off the flow of gases around the oven and a second 50 damper for controlling the flow of gases through the said vertical front passage whilst the flow through the said vertical rear passage is uninterrupted.

2. A cooking stove and water heater comprising,—a fireplace, a water heater located 60 behind the fireplace and comprising front, intermediate and rear water containing elements spaced from each other to form vertical front and rear passages for the fire gases, a baking oven located at one side of the fireplace, means around the oven 65

forming passages for directing the fire gases over the top of the oven, thence down one side, and thence beneath the bottom thereof, means forming a passage for directing the said gases from beneath the oven to the 70 said vertical rear passage between the intermediate and rear water containing elements, and control means for the fire gases comprising a damper located in the gas passage beneath the oven for shutting off the 75 flow of gases around the oven and a second damper located between the vertical front and rear passages for controlling the flow of gases through the said front passage whilst the flow through the said rear passage 80 is uninterrupted.

3. A cooking stove and water heater comprising,—a fireplace, a water heater located behind the fireplace and comprising front, intermediate and rear water containing elements spaced from each other to form vertical front and rear passages for the fire gases, the intermediate water containing element having an opening at the upper 85 edge thereof, a baking oven located at one 90 side of the fireplace, means around the oven forming passages for directing the fire gases over the top of the oven thence down one side and thence beneath the bottom thereof, means forming a passage for directing the said gases from beneath the oven to the said vertical rear passage between the intermediate and rear water containing elements, and control means for the fire gases comprising a damper for shutting 95 off the flow of gases around the oven, a second damper for controlling the flow of gases through the said vertical front passage whilst the flow through the said rear 100 passage is uninterrupted, and a movable member closing the said opening in the intermediate element and carrying the last mentioned damper.

4. A cooking stove and water heater comprising,—a fireplace, a water heater located 110 behind the fireplace and comprising front, intermediate and rear water containing elements spaced from each other to form vertical front and rear passages for the fire gases, the intermediate water containing element having openings at the upper and lower edges thereof, a baking oven located at one side of the fireplace, means around the oven forming passages for directing the fire gases over the top of the oven thence down one side and thence beneath the bottom thereof, means forming a passage for directing the said gases from beneath the oven through the said opening in the lower edge of the intermediate element to the said 115 vertical rear passage between the intermediate and rear water containing elements, and control means for the fire gases comprising a damper for shutting off the flow of gases around the oven, a second damper 120

for controlling the flow of gases through the said vertical front passage whilst the flow through the said vertical rear passage is uninterrupted, and a moveable member carrying the latter damper and mounted in the upper opening in the said intermediate element.

In testimony whereof I affix my signature in presence of two witnesses.

FRITZ ALBERT PETTERSSON.
